UNITED STATES PATENT OFFICE

ADOLPH NELSON, OF HUGO, COLORADO

AUTOMATIC LUBRICATING VALVE

Application filed December 27, 1927. Serial No. 242,919.

This invention relates to automatic lubricating valves and is an improvement over my application of the same title, Serial Number 151,553, filed November 29, 1926, 5 which has become Patent No. 1,672,079 issued June 5, 1928. The principal objects of my present invention are to provide a lubricating valve adapted to be readily attached to drill machines, cylinders and the like, and whereby 10 a jet of compressed air or steam from the operating medium may be directed through the valve and thus cause the oil or other lubricant to be forced through the machine or other mechanism that is to be lubricated. 15 With the above and other objects in view which will appear as the description proceeds, the invention consists of the novel construction, combination and arrangement of parts hereinafter described and claimed. 20 These objects are accomplished by devices illustrated in the accompanying drawings, wherein:—

Figure 1 is a view in side elevation of the device;

25 Fig. 2 is a view in end elevation of the same;

Fig. 3 is a view in vertical section taken substantially on a broken line 3, 3 of Fig. 2;

Fig. 4 is a view in vertical section taken on 30 a broken line 4, 4 of Fig. 1;

Fig. 5 is a view in horizontal section taken on a broken line 5, 5 of Fig. 4;

Fig. 6 is a detail perspective view of the plug valve;

35 Fig. 7 is a view in vertical section of a modified form; and

Fig. 8 is a vertical section of another modified form.

Referring to the drawings throughout 40 which like reference numerals designate like parts, the numeral 5 indicates the valve casing as a whole that is provided with a boss 6 on one side and having a conically tapered valve seat 7 passing through same and adapted to receive a conical plug valve 8. The intake end of said valve seat is provided with a reducer nut 9 having an inwardly tapered opening 10. An intake elbow member 11 has its inner end tapered at 12 to fit within said 45 tapered opening and a spring 13 may be in-

terposed between the end of the plug valve and the inner end of the member 11 to hold same against its tapered seat.

The plug valve 8 is hollow as shown at 14 with its open end in communication with the intake 11. A hole 15 through the wall of said plug valve is adapted to register with a passage 16 extending through the wall of the casing 5 to a point at the remote end of a reservoir 17 which serves as a container for the lubricant. A slot 18, at the same time, registers with an outlet passage 19 extending through the base of the casing 5. Said casing is provided with an annular flange 20 that is adapted to form a connection with a compressed air mine drilling machine or the like and same may be readily secured thereto by means of bolts passing through lugs 21 as will be readily understood. Said flange may be threaded for connection as shown in Fig. 8 if desired.

It will be understood that the hole 15 is in communication with its passage 16 and the slot 18 is in communication with its outlet 19 at one and the same time. Thus part 75 of the air or steam entering the hollow plug valve 8 from the supply pipe 11 will pass through the outlet passage into the drill or other machine and part of the air or steam will pass into the reservoir 17 thus causing 80 a pressure therein.

A nozzle member 22 projects through a hole 23 in the boss 6 into the reservoir 17. Said nozzle is exteriorly provided with a handle 24 and has an annular groove 25 with holes 26 that are adapted to register with a passage 27 that communicates with a hole 28 through the plug valve 8. Said hole communicates with the outlet passage 19 and it will thus be seen that the pressure in the reservoir will force the lubricant into the machine or engine that is to be lubricated as clearly shown in the drawings. The reservoir may be filled through the hole 23 by removing the nozzle member 22.

90 The plug valve 8 is manipulated by a handle 29 having indentations 30 in the underside of its hub portion that register with a pin 31 set in the casing 5 and impelled by a spring 32. In the drawings said handle is 95 100

shown with the plug valve in the operative position with the pressure medium passing freely through the apparatus. By shifting said handle to the other indentations the valve may be shut off as will be understood.

5 As a means for passing water through the device into the drill machine attached thereto I have provided a supply pipe 33 connected with a passage 34 in communication 10 with a flush pipe 35 installed in a column 36 passing centrally through the reservoir 17. A nut 37 having a groove 38 in its end is adapted to register with the passage 34 and provide means for controlling the water supply.

15 Referring to Figs. 3 and 6, I have provided a spiral groove 42 in the plug valve 8 one end of which is adapted to register with the passage 16 when said valve is shut off while 20 the other end registers with the outlet 19 for the purpose of releasing the pressure within the reservoir 17 if desired.

25 In the modified form of apparatus shown in Fig. 7 the construction is substantially the same as in the preferred form although the position of several details is somewhat shifted. In the form shown in Fig. 8 I have provided a piston 39 for the reservoir 17. Said piston is provided with a shaft 40 projecting 30 exteriorly of the reservoir and provided with graduations which serve as a gauge to indicate the amount of lubricant within said reservoir. In this form I also provide a passage 41 between the valve seat 7 and reservoir that is adapted to register with the slot 35 18 when the plug valve 8 is in the reverse position so the compressed air may be diverted to lift the piston when the reservoir is empty.

35 Having thus described my invention what 40 I claim and desire to secure by Letters Patent is:

45 1. A lubricating valve comprising a casing having a reservoir therein, a hollow plug valve having a hole adapted to register with a passage in communication with the remote end of the reservoir, said plug valve having a slot arranged to register with a discharge passage, a nozzle member for the reservoir having a groove and holes arranged 50 to register with a passage and hole through the plug valve to form a communication from the reservoir to the discharge passage.

55 2. A lubricating valve comprising a casing having a reservoir therein, a hollow plug valve having a hole adapted to register with a passage to form a communication with the remote end of the reservoir, said plug valve having a slot arranged to register with a discharge passage at one and the same time the 60 foregoing communication is established, a nozzle member for the reservoir having a groove and holes arranged to register with a passage and hole through the plug valve to form a communication from the reservoir 65 to the discharge passage.

3. A lubricating valve comprising a casing having a reservoir therein, a hollow plug valve having a hole adapted to register with a passage to form a communication with the remote end of the reservoir, means for manipulating the plug valve, said plug valve having a slot arranged to register with a discharge passage, a nozzle member for the reservoir having a groove and holes arranged to register with a passage and hole through the plug valve to form a communication between the reservoir and discharge passage.

70 75 In witness whereof, I hereunto subscribe my name this 21st day of December, A. D. 1927.

80 ADOLPH NELSON.
